UNITED STATES PATENT OFFICE.

ALBERT K. WATCHER, OF CINCINNATI, OHIO.

CROSS-FEED MECHANISM FOR MACHINE TOOLS.

Application filed November 22, 1920. Serial No. 425,714.

An object of my invention is to provide a cross feed for a shaper, in which there is a positive mechanism for feeding the work only on the back stroke of the shaper.

5 Another object is to provide a device for the purpose stated that will operate uniformly, regardless of the direction of the cross feed.

Another object is to provide a device 10 wherein it will be possible to accurately adjust the cross feed.

Another object is to provide a cross feed mechanism in which all of the parts subject to wear are stationary at all times except 15 during the feeding operation.

These and other objects are attained by the means described herein and disclosed in the accompanying drawing in which:—

Fig. 1 is a side elevation of a shaper upon 20 which a device embodying my invention is mounted.

Fig. 2 is an enlarged sectional view on line 2—2 of Fig. 1, parts being broken away.

Fig. 3 is a view on line 3—3 of Fig. 2.

25 Fig. 4 is an enlarged sectional view on line 4—4 of Fig. 3.

Fig. 5 is an enlarged, sectional view on line 5—5 of Fig. 3.

My invention comprises a rotatable driven 30 shaft b^2 actuated by a cam a^{12} mounted on the bull wheel shank a^2 and operating upon a cross feed shaft D.

The shaper A has the shaft a extending 35 from the side of its base a' . Internally to the base and mounted concentric with the shaft a is a bull wheel, the shank a^2 of which is shown in the drawings. The bull wheel is actuated from the pulley shaft a^3 by any suitable means, such as gears, in a manner 40 well known and requiring no further explanation or illustration. The shank a^2 of the bull wheel is keyed to the sleeve a^4 which is mounted upon the shaft a and extends into the bore of the bull wheel shank. The 45 shaft a extends thru the sleeve a^4 . The outer end a^5 of the shaft a is screw threaded and the lock nut a^6 is mounted upon the threaded section of shaft a and abuts the sleeve a^4 , and the bull wheel, the sleeve a^4 , and the

shaft a , rotate as a whole. A square head 50 is formed on the outer end of shaft a to permit adjustment of the stroke of the ram A'. A housing a^7 is mounted upon the base of the shaper and encases the bull wheel shank. The housing a^8 is mounted upon the sleeve a^4 and housing a^7 and encases the mechanism now to be described.

A flange a^9 formed on the sleeve a^4 serves as a bearing upon which one end of the housing a^8 is mounted. The shoulder a^{10} 60 resulting from the formation of the flange a^9 abuts the bull wheel shank. The shoulder a^{11} , resulting in like manner from the formation of the flange a^9 , abuts the cam a^{12} mounted upon and keyed to the sleeve a^4 , 65 interiorly to the housing a^8 . An oil chamber a^{13} is formed in the bottom of the housing a^8 and has a drain port a^{14} in it. The plug a^{15} seats in the drain port. The sleeve a^4 is mounted upon bearing a^{16} mounted in the 70 outer wall of the housing a^8 . Suitable packing a^{17} is mounted in the bearing a^{16} and prevents leakage of oil from the oil chamber a^{13} . Extending from the housing a^8 and preferably at right angles to the shaft 75 a is the driven shaft b . Shaft b comprises the sleeve b' and the longitudinally reciprocating shaft b^2 , the reciprocating shaft b^2 extending into and telescoping into the sleeve b' . The key b^3 joins the sleeve and reciprocating shaft. Mounted upon the sleeve b' is a sleeve bearing b^4 within which sleeve b' can rotate, and upon which is mounted the 80 slideable housing b^5 . The sleeve b^4 is pressed into the housing a^8 , and extends into the interior thereof. Contained within the housing a^8 is the friction plate b^6 which extends into and is keyed to the inner end of the sleeve b' , by means of the keys b^7 . The friction plate b^6 abuts and extends beyond the inner ends of the sleeves b' and b^4 . An adjustment disk b^8 is mounted upon the sleeve b^4 interiorly to the housing a^8 and immediately adjacent to such housing. The disk b^8 has a series of teeth b^{10} upon its periphery. A pin b^{11} is mounted in the bore b^{12} in the boss b^{13} in the housing a^8 and is held in engagement with the teeth on the 85 90 95

- disk b^9 by means of a spring b^{12} contained in the bore b^{13} of the boss b^{34} . A lug b^{14} is mounted on the disk b^9 . An adjustable abutment screw b^{30} is mounted on the lug b^{14} .
- 5 A lever b^{15} is mounted on the disk b^9 and extends thru a slot a^{18} in the housing a^8 . The disk b^9 engages the housing a^8 adjacent to slot a^{18} and closes such slot. Mounted on the sleeve b^4 and abutting the disk b^9 at one end and the flange b^8 of plate b^6 at its other end is the oscillating arm b^{16} . Suitable packing b^{31} encased within the oscillating arm prevents escape of the oil from within the casing a^8 . The arm b^{16} has a lug b^{17} 10 extending therefrom adapted to engage the abutment screw b^{30} on the lug b^{14} on the disk b^9 . A roller b^{18} is mounted upon the arm b^{16} and is adapted to engage the face a^{19} of the cam a^{12} . A pawl b^{19} is mounted 15 on the arm b^{16} and engages the teeth b^{32} of the ratchet wheel b^{20} mounted upon the shoulder b^{21} of the friction plate b^6 . A washer b^{22} is mounted on the shoulder b^{21} of the friction plate between the flange b^8 20 on the friction plate and the ratchet wheel b^{20} . Formed on the friction plate b^6 is a threaded plug b^{23} , and mounted upon this plug are the washer b^{24} , the springs b^{25} and the lock nuts b^{26} . The springs b^{25} 25 have sufficient tension to press the ratchet wheel b^{20} , the washer b^{22} and the flange b^8 upon one another that normally these members rotate as a unit. Mounted upon the arm b^{16} is the coil spring b^{27} , one end of which is secured to the disk b^9 and the other end of which engages the arm b^{16} .
- 30 Upon the forward end of the shaft b^2 is mounted a bevel gear b^{33} which engages the bevel gears d' and d^2 adapted to actuate the cross feed shaft D.
- 35 The cross feed shaft D is cased within the housing d , and has mounted upon it the bevel gears d' and d^2 , and the double clutch sleeve d^3 . The gears d' and d^2 are loosely mounted on the shaft D and at all times engage the beveled gear b^{33} . The double clutch sleeve d^3 is keyed to the shaft D and has teeth formed upon its opposite ends that are adapted to engage the teeth d^4 and d^5 upon 40 the gears d' and d^2 respectively, whereby the rotation of the shaft D may be reversed. A clutch lever d^6 extends thru the housing d whereby the double clutch sleeve may be actuated. The clutch lever d^6 has in it, inferiorly to housing d , a bore d^{10} in which are mounted the ball d^{11} and spring d^{12} . The spring holds the ball upon the interior of the housing d and retains the ball in one of the seats d^{13} formed in the housing and holding 45 the double clutch sleeve in or out of engagement with the bevel gears d' and d^2 . A hand wheel d^7 is mounted upon one end of the shaft D and the other end of the shaft D extends into a threaded block d^8 in the work support d^9 mounted upon the front of the 50
- 60
- 65

base of the shaper. The work support d^9 is adapted to be adjusted to various elevations in a well known manner.

The operation of my device is as follows:

The bull wheel shank a^2 is driven from the pulley shaft a^3 by means of suitable gears. The cam a^{12} mounted on the sleeve a^4 rotates in unison with the bull wheel and shaft a and as it is revolved it strikes the roller b^{18} mounted on the arm b^{16} , thereby pushing the arm b^{16} about the axis of the shaft b^2 . The pawl b^{19} mounted on the arm b^{16} is in engagement with the teeth of the ratchet wheel b^{20} and revolves the ratchet wheel about its axis. The springs b^{25} hold the ratchet wheel b^{20} , washer b^{22} and friction plate b^6 in frictional engagement whereby the friction plate is revolved. The friction plate is keyed to the sleeve b' which in turn is keyed to the shaft b^2 having the gear b^{33} mounted upon it. The arc thru which the arm b^{16} is moved, is determined by the relation between the roller b^{18} and the cam a^{12} . When the lever b^{15} , see Fig. 2, is moved in a clock-wise direction, screw b^{30} on the lug b^{14} on the disk b^9 pushes the lug b^{17} on the arm b^{16} before it thereby moving the roller b^{18} away from the cam a^{12} . When the lever b^{15} is moved to its limit in a clock-wise direction, the roller will be held outward beyond the cam a^{12} and the cam a^{12} will at no time during any of its revolutions engage the roller b^{18} , and therefore the shaft b^2 will not be actuated. As the lever b^{15} is moved in a counter-clock-wise direction, the roller approaches the cam a^{12} and at first engages the outermost portion of the cam only. As the lever is moved farther in a counter-clock-wise direction the roller engages more and more of the cam's face, and consequently as the cam revolves it will move the roller thru an arc in proportion to the extent to which the roller is moved toward the bull wheel shank a^2 . The spring b^{27} is tensioned as the roller is actuated by the cam and is moved from its normal position, consequently the roller tends to assume a position in which the spring will be untensioned and therefore will resist the cam and tend to return to its normal position. The roller will return to its normal position as soon as the cam permits it to do so. In the normal position of the roller, the lugs b^{14} and b^{17} are in engagement. Should it occur that for any unforeseen reason, the rotation of the shaft b^2 or the movement of the work support d^9 is blocked, the spring b^{25} and washer b^{22} will permit the ratchet wheel b^{20} to slip upon the washer and to move about its axis without actuating the friction plate b^6 .

The movement of the shaft b^2 is transmitted to cross feed shaft D by means of the bevel gears b^{33} , d' and d^2 and the double clutch d^3 . The cam a^{12} is so mounted on the sleeve a^4 that the shaft b^2 will be actuated

only during such a time when the ram A' of the shaper is on its back stroke, whereby the work support d⁹ will be fed across the shaper only at such a time when the ram A' is on 5 its back stroke. The fixed relation of the several parts, due to the fact that they are keyed to one another assures the feed upon the back stroke.

When the clutch d³ is in its central or 10 neutral position the work support d⁹ is not fed. As an added precaution, because of accidental contact of a workman with the lever d⁸ controlling the clutch d³, the roller b¹⁸ may be moved outward beyond the cam 15 a¹² by means of the lever b¹⁵ thereby avoiding any movement of the shaft b². The feed of the mechanism can be readily determined by means of the indicator plate b²⁸ mounted upon the housing a⁸ over which the index 20 finger b²⁹ mounted on the lever b¹⁵ extends. The pin b¹¹ engaging in the teeth b¹⁰ on the disk b⁹ holds the disk b⁹ in any adjusted position thereby assuring a uniform feed.

The telescopic shaft b² and sleeves b', b⁴ 25 and housing b⁵ permit the work support d⁹ to be raised or lowered. The housing a⁸ is adapted to move about the housing a⁷ and sleeve a⁴, and the housing d is adapted to move about the cross feed shaft D, thereby 30 avoiding any strain upon any of the parts due to the movement of the work support d⁹.

As the roller is moved by the cam, the driven shaft is actuated, and as soon as the 35 cam has moved the roller to the limit of the cam's path, the pawl ratchets over the ratchet wheel. It is during the time while the pawl moves toward its normal position that the ram A' is making its cutting stroke, wherefore it is impossible for the work 40 support to be fed at any time except during the back stroke of the ram. The roller is moved out of the path of the cam by means of the lever b¹⁵ and the adjustment disk, when no feed is wanted, therefore, none of 45 the parts except the cam will be actuated.

What I claim is:

1. In a feed mechanism the combination with a drive shaft, of a cam mounted on the drive shaft, a driven shaft for arcuate adjustment about the drive shaft and comprising a sleeve and a longitudinally reciprocating shaft extending into the sleeve and keyed thereto, a ratchet wheel mounted on the sleeve, an oscillating arm mounted on the sleeve and adapted to be extended into the path of the cam, a pawl mounted on the oscillating arm and engaging the ratchet wheel, an adjustable work support, a cross feed shaft engaging the work support, and means to transmit the movement of the driven shaft to the cross feed shaft.

2. In a feed mechanism the combination with a drive shaft, of a cam mounted on the drive shaft, a driven shaft for arcuate adjustment about the drive shaft and comprising

ing a sleeve and a longitudinally reciprocating shaft extending into the sleeve and keyed thereto, a friction plate fixedly mounted on the sleeve, a ratchet wheel mounted revolvably upon the friction plate, yieldable means 70 mounted upon the friction plate and retaining the ratchet wheel in frictional driving contact with the friction plate, an oscillating arm mounted on the sleeve, a pawl mounted on the arm and engaging the 75 ratchet wheel, an adjustable work support, a cross feed shaft engaging the work support, and means to transmit the movement of the driven shaft to the cross feed shaft.

3. A feed mechanism comprising a drive shaft, a cam mounted on the drive shaft, a driven shaft, a ratchet wheel mounted on the driven shaft, a disc mounted for rotatable adjustment upon the driven shaft, a lug on the adjustable disk, an oscillating arm 85 mounted on the driven shaft, a lug on the oscillating arm adapted to engage the lug on the adjustable disk, a pawl mounted on the oscillating arm and engaging the ratchet wheel, and means normally holding the lug 90 on the oscillating arm in engagement with the lug on the adjustable disk and adapted to yieldingly retain the oscillating arm in the path of the cam.

4. A feed mechanism comprising a drive shaft, a cam mounted on the drive shaft, a driven shaft, a friction plate mounted fixedly on the driven shaft, a ratchet wheel mounted revolvably upon the friction plate, a washer interposed between the friction plate and the 100 ratchet wheel, means mounted on the friction plate yieldably retaining the ratchet wheel and the washer in frictional engagement with one another and with the friction plate, a disc mounted for rotatable adjustment upon a driven shaft, a lug on the adjustable disc, an oscillating arm mounted on the driven shaft, a lug on the oscillating arm adapted to engage the lug on the adjustable disk, a pawl mounted on the oscillating arm 105 and engaging the ratchet wheel and means normally holding the lug on the oscillating arm in engagement with the lug on the adjustable disk and adapted to yieldingly retain the oscillating arm in the path of the 110 cam.

5. A feed mechanism comprising a drive shaft, a cam mounted on the drive shaft, a driven shaft at an angle to the drive shaft, 120 a ratchet wheel mounted on the driven shaft, a disc mounted for rotatable adjustment upon the driven shaft, a lug on the adjustable disk, an oscillating arm mounted on the driven shaft, a lug on the oscillating arm adapted to engage a lug on the adjustable 125 disc, a pawl mounted on the oscillating arm and engaging the ratchet wheel, and means normally holding the lug on the oscillating arm in engagement with the lug on the adjustable disk and adapted to yieldingly re- 130

tain the oscillating arm in the path of the cam.

6. A shaper cross feed mechanism comprising a drive shaft, a sleeve mounted on the drive shaft, a cam mounted on the sleeve, a housing mounted movably upon the sleeve and having an oil chamber formed therein, a driven shaft extending thru the housing, a friction plate mounted on the driven shaft 5 interiorly to the housing, a ratchet wheel mounted revolubly on the friction plate, an oscillating arm mounted on the driven shaft adapted to be moved into various degrees of registration with the cam, a pawl mounted on the oscillating arm and engaging the ratchet wheel, a cross feed shaft and means for transmitting the movement of the driven shaft to the cross feed shaft.

7. A feed mechanism comprising a drive shaft, a cam mounted on the drive shaft, a driven shaft, a ratchet wheel mounted on the driven shaft, an oscillating arm mounted on the driven shaft, a pawl mounted on the oscillating arm and engaging the ratchet wheel, a lug on the oscillating arm, a roller mounted on the oscillating arm in alignment with the cam, a disc mounted for rotatable adjustment upon the driven shaft, means to retain the disk in an adjusted position, a lug on the disk adapted to normally engage the lug on the oscillating arm, and means mounted on the disk and on the arm adapted to retain the lugs in normal relation and to yieldingly retain the roller in the path of the cam, the adjustable disk, the oscillating arm and the roller being adjustable to such positions whereby the roller may be interposed in the path of the cam to various degrees of registration therewith.

8. A feed mechanism comprising a drive shaft, a sleeve mounted fixedly on the drive shaft, a cam mounted on the sleeve, a slotted housing mounted movably upon the sleeve, a driven shaft extending into the housing, a ratchet wheel mounted on the driven shaft interiorly to the housing, an oscillating arm mounted on the driven shaft, a pawl mounted on the arm and engaging the ratchet wheel, a roller on the oscillating arm adapted to be moved into the path of the cam, a lug on the oscillating arm, a disk mounted for rotatable adjustment upon the driven shaft interiorly to the housing and adapted to cover the slot in the housing, a lever mounted on the disk and extending thru the slot in the housing, a lug on the disk adapted normally to engage the lug on the oscillating arm, teeth on the disk, a pin mounted upon the housing, means to retain the pin in yieldable frictional engagement with the teeth on the disk, and a spring engaging the disk and the oscillating arm and adapted to yieldingly retain the lugs in their normal relation.

9. A feed mechanism comprising a drive shaft, a sleeve mounted fixedly on the drive shaft, a cam mounted on the sleeve, a slotted housing mounted movably upon the sleeve, a driven shaft extending into the housing, a friction plate mounted on the driven shaft interiorly to the housing, a ratchet wheel mounted revolubly upon the friction plate, means holding the ratchet wheel in yieldable frictional engagement upon the friction plate, an oscillating arm mounted on the driven shaft, a pawl mounted on the arm and engaging the ratchet wheel, a lug on the arm, an adjustable disk mounted on the driven shaft interiorly to the housing and covering the slot in the housing, a lever extending thru the slot in the housing, a lug on the disk normally engaging the lug on the arm, means to hold the disk in an adjusted position, and a coiled spring mounted about the driven shaft and engaging the disk and the arm, the spring being adapted to yieldingly retain the lugs in their normal positions.

10. A feed mechanism comprising a drive shaft, a sleeve mounted fixedly on the drive shaft, a cam mounted on the sleeve, a slotted housing mounted movably upon the sleeve, a driven shaft extending into the housing, a friction plate mounted on the driven shaft interiorly to the housing, a ratchet wheel mounted revolubly upon the friction plate, means holding the ratchet wheel in yieldable frictional engagement upon the friction plate, an oscillating arm mounted on the driven shaft, a pawl mounted on the arm and engaging the ratchet wheel, a lug on the arm, an adjustable disk mounted on the driven shaft interiorly to the housing and covering the slot in the housing, a lever extending thru the slot in the housing, a lug on the disk normally engaging the lug on the arm, means to hold the disk in an adjusted position, an adjustable work support, and a feed shaft engaging the work support and means to transmit the movement of the driven shaft to the feed shaft.

11. A shaper cross feed mechanism comprising a drive shaft, a housing enclosing one end of the drive shaft and mounted for arcuate adjustment about the drive shaft, the housing having an oil chamber formed within it, a driven shaft extending into the housing and capable of arcuate adjustment with the housing about the drive shaft, a cam mounted on the drive shaft and contained within the housing, and means carried by the driven shaft for adjustment toward and away from the cam whereby to effect variable contacts between such means and the cam for modifying the extent of movement of the driven shaft per revolution of the drive shaft.

12. A shaper feed comprising a drive shaft, a driven shaft mounted for arcuate

movement about the drive shaft, a cam on the drive shaft, the cam having an operating face all portions of which extend in substantial parallelism with the axis of the driven shaft, and a member mounted on the driven shaft and adjustable toward and away from the operating face of the cam

for variable contact with the cam face for imparting variable and intermittent movement to the driven shaft.

10

In testimony whereof, I have hereunto subscribed my name this 15th day of November, 1920.

ALBERT K. WATCHER.
